2,682,488

METHOD OF CENTRIFUGAL PURIFICATION
OF SUGAR

Ernest G. Kochli, Scarsdale, N. Y., and Charles A. Olcott, West Milford, N. J.

Application July 18, 1949, Serial No. 105,364

2 Claims. (Cl. 127—64)

1

This invention relates to washing apparatus for centrifugal machines such as are used, for example, in the manufacture of sugar and similar solids and more specifically to methods for controlling the distribution of the washing liquid used with said centrifugal machines.

It is an object of this invention to improve the washing of sugar and the like in centrifugal machines.

When sugar or similar material is treated in centrifugal machines, it is customary to spin the wet mass to throw off the mother liquor and after this liquor has been spun off and while the machine is still rotating at high speed, it is the practice to spray water or other washing fluid onto the material. In typical apparatus heretofore used, a single spray for the washing fluid is supported from the curb surrounding the centrifugal basket and all of the sugar is washed by the fluid from this spray.

Applicants have discovered that the sugar washing produced by this prior arrangement is not satisfactory. Some of the sugar shows evidence of being over-washed (which means that the grains are unnecessarily dissolved) while other parts are under-washed (which means that they have more color, thus lowering the color standard of the entire batch). The present invention, in one of its primary aspects, relates to the improvement of the color standard of washed sugar and the like.

It is another object of this invention to produce sugar and the like not subject to the disadvantages just described in the preceding paragraph.

It is still another object of this invention to make more uniform the washed grains of sugar and the like.

Applicants have also discovered that in purging, that is, in spinning off the green syrup before washing, the sugar at the top of the sugar wall is normally of superior quality, requiring relatively little washing, while the sugar at the bottom of the basket contains more impurities and frequently the sugar wall is thicker, requiring more washing. They have taken advantage of this discovery in the present invention.

The above and related objects are attained in accordance with the invention by providing, as an exemplary embodiment thereof, a sugar spraying apparatus having two or more pipes each with a nozzle for spraying sugar in the basket, each spray being regulated both as to time of application and amount of water applied. One spray is located near the top of the basket where the

2

syrup is quickly spun off and is started a predetermined time, say 40 seconds, after the machine is started and stopped at say 45 seconds after the start of the machine, giving a total spraying time of 5 seconds. The spray for washing the lower part of the sugar is started at say 43 seconds after the start, thus giving a little more time to get rid of the green syrup, and stopped at say 50 seconds after the start, thus giving a longer spraying time (7 seconds) and consequently more washing than is applied to the sugar at the top. If desirable a larger spray nozzle can be used for washing the bottom of the basket in order to get more water on quickly. Also for a very deep basket, three or more spray nozzles each separately controlled can be used. Each spray nozzle is controlled by a three-port, two position valve operated by a solenoid.

While each solenoid can be manually controlled by a push-button, automatic control means for this solenoid is also provided in accordance with this invention. An exemplary embodiment of this control means (for a two spray device) comprises a limit switch operated by the movement of the mixer gate, for example, and adjustable electric timer means comprising a master timer and two local timers. The limit switch is located at a point where it will be operated by the normal movement of the mixer gate used to load the centrifugal. The washing cycle does not begin until the gate is closed. Then the master timer runs for a predetermined time according to its setting and energizes one of the local timers which simultaneously energizes its solenoid valve, starting the spraying. A predetermined time thereafter the second local timer is started running by the closing of a second circuit by the master timer. This second timer upon its actuation immediately energizes its solenoid and starts its spray. The timers "time out" at times dependent on their individual adjustments to stop the spraying. Both local timers remain in a timed-out position while the centrifugal is running to spin off the wash water and during the periods of braking and discharging the basket but, if desired and in accordance with well-known practice, the master timer or controller can be used to control the times of these operations also.

The invention will be more readily understood by referring to the following description taken in connection with the accompanying drawing forming a part thereof, in which:

Fig. 1 is a schematic diagram of a rotating basket for a sugar centrifugal machine and spray-

ing apparatus, including two spaced spray members and control apparatus therefor, for washing the grains of sugar in the basket;

Figs. 2 and 3 are schematic diagrams used to indicate the positions of each of the solenoid-controlled, three-port valves shown in the arrangement of Fig. 1 when each solenoid is, respectively energized and de-energized; and

Fig. 4 illustrates the sequence of the spraying operations.

Referring more specifically to the drawing, Fig. 1 shows, by way of example to illustrate the invention, a basket 10 of a sugar centrifugal and associated apparatus for controlling the washing of the massecuite therein at the proper times in each centrifuging cycle. The basket 10 is surrounded by a suitable outer casing 11 which has an opening 12 at the top thereof through which the basket can be loaded with massecuite from a suitable mixer tank (not shown). The basket is supported and rotated by a spindle 13 which is driven by any well-known means such as, for example, an individual electric motor positioned above it. Supported from the outer casing 11 by any suitable means are pipes 14 and 15 terminating, respectively, inside the basket at spray members 16 and 17 and at valves 18 and 19 outside the basket.

The valve 18 has three ports, one of them leading to the pipe 14, a second being connected by a pipe 20, having a hand valve 21 therein, to a suitable source of washing fluid such as a water header 22, and the third one being connected to a drip pipe 23 which may lead to a receptacle (not shown) which can be connected through a pump to the water header. Reference will now be made to Figs. 2 and 3 which represent schematically the "on" and "off" positions of the valve 18. In the "on" position (Fig. 2), washing fluid from the header 22 is applied, through the open valve 21, the pipe 20, valve 18, pipe 14, hand valve 24, pipe 25 and spray 16, to the sugar grains in the basket 10 at the proper time in each centrifuging cycle. When the valve 18 is turned to the "off" (Fig. 3) position, the pipe 20 from the valve to the header 22 is blocked and the passage from the pipe 14 to the drip pipe 23 is opened. If the valve 18 is located below the level of the spray member 16, the liquid in the spray pipe 25 forms a siphon which draws the liquid back through this pipe away from the spray nozzle 16, and down through the drip 23, instead of allowing it to dribble on the sugar which has been dried by the centrifugal action of the rotating basket 10, as described in Patent 2,461,741 issued February 15, 1949 to E. G. Kochli and C. A. Olcott.

The valve 18 can be operated by hand between its "on" and "off" positions, at the proper times in each centrifuging cycle, but preferably this operation is accomplished by means of a solenoid 26 which is energized either by a source of power 27 and a manually operated switch 30 operating to connect together contacts 28 and 29, or by automatic means to be described below after the description of the valve 19 and its connections.

The valve 19 is similar to the valve 18 and the diagrams shown in Figs. 2 and 3 apply to it as well as to valve 18. Valve 19 is connected to the header 22 by means of pipe 20 and to the drip pipe 23. Its third port is connected through the pipe 15 having a hand valve 31 therein to the lower spray nozzle 17. Valve 19 is actuated between its "on" and "off" positions by means of solenoid 32 and source of power 33, the circuit

being closed by manual switch 36 bridging contacts 34 and 35 or by the automatic means to be now described.

When the hand-operated switches are left open (as indicated in Fig. 1) they can be operated by automatic means comprising the master timer 37 and local timer mechanisms 38 and 39, respectively connected to operate solenoids 26 and 32 at the proper times in the washing cycle. Timers 37, 38 and 39 are of any suitable form and are sold commercially by a number of suppliers so their internal mechanism and connections need not be described here. Master timer 37 is initiated by the closing of a suitable switch 40 which can be a manually operated switch or a limit switch operated by closing of the gate of the centrifugal mixer (not shown) supplying the basket 10 with massecuite. Closing of the switch 40 supplies power from the lines L1 and L2 to the master timer 37 and starts its motor running and at the same time supplies power over line 41 to start the motor driving centrifugal basket 10. After a predetermined interval from the time the motor of the centrifugal has been started for the drying operation, the master timer 37 closes a set of contacts to apply power over line 42 to start running the motor in timer 38 and over line 43 to start the motor in timer 39. After a second predetermined interval making a total of, for example, 40 seconds after the centrifugal motor has been started, the timer 38 closes a set of contacts to operate solenoid 26. This operates valve 18 to the "on" position and applies spray water from header 22 to the spray nozzle 16, the amount of water being controlled by valve 24. In the meantime, the timer motor in timer 39 has also been operating and after a total interval of, for example, 43 seconds from the time of starting of the motor of the centrifugal, a set of contacts in this timer is closed and solenoid 32 is operated to move valve 19 to the "on" position and apply spray water from the header 22 to the lower spray nozzle 17. Power for the timers 38 and 39 can be obtained from the lines L1 and L2 or from local sources. The timer motors in timers 38 and 39 run for predetermined intervals of, for example, 5 and 7 seconds, respectively, after closing their contacts (as above described) and then they "time-out", opening these contacts and causing the solenoids 26 and 32 to become deenergized and operate the valves 18 and 19, respectively, to the "off" positions shutting off in turn the nozzles 16 and 17. Fig. 4 shows the periods of operation of the spray nozzles 16 and 17 and the overlapping of these periods of spraying. Both timers 38 and 39 remain "timed-out" during the spinning off of the wash water, and during the braking and discharging operations of the basket. The master timer 37 can be used to control these operations, if desired, and timers or controllers for this purpose are well-known.

It is obvious that the specific times of spraying and the durations of spraying periods are given merely by way of example and can be varied as desired. The amount of water for each spray nozzle can be varied by settings of the hand valves 24 and 31. One of the nozzles (as, for example the nozzle 17) can be made larger than the other in order to get more water on more quickly. Usually the bottom requires more water than the top. For a very deep basket, three or more spray nozzles, each separately controlled for times of operation and amount of water sprayed, can be used.

By means of the controlled method of spraying described herein, a much more even washing of the sugar can be obtained than in the arrangements heretofore used.

Obviously various changes can be made in the embodiment described without departing from the spirit of the invention the scope of which is indicated in the claims.

What is claimed is:

1. The improvement in the method of centrifugal purification of sugar and the like wherein there is a purging treatment of the sugar material in the centrifugal followed by the centrifugal washing of said material, which comprises washing the top of said material during a period which starts earlier and uses less washing liquid than the period in which the bottom of said material is washed.

2. The improvement in the method of centrifugal purification of sugar and the like wherein there is a purging treatment of the sugar material in the centrifugal followed by the centrifugal washing of said material, which comprises washing the top of said material during a period which starts earlier, has a shorter spraying time

and uses less washing liquid than the period in which the bottom of said material is washed.
